CLAIM

The ornamental design for a grab rail assembly for a roof assembly of a work vehicle, substantially as shown and described.

DESCRIPTION

FIG. 1 is a back perspective view of a grab rail assembly for a roof assembly of a work vehicle;

FIG. 2 is a front perspective view of the grab rail assembly;

FIG. 3 is a back view of the grab rail assembly;

FIG. 4 is a front view of the grab rail assembly;

FIG. 5 is a right side view of the grab rail assembly;

FIG. 6 is a left side view of the grab rail assembly;

FIG. 7 is a top view of the grab rail assembly; and,

FIG. 8 is a bottom view of the grab rail assembly.

In the drawings, the broken lines depict environmental subject matter only and form no part of the claimed design.

1 Claim, 6 Drawing Sheets
